(57) **CLAIM**

The ornamental design for a kayak illumination device, as shown and described.

DESCRIPTION

FIG. 1 is a front perspective view of a kayak illumination device illustrating my new design;

FIG. 2 is a side view of the design of FIG. 1;

FIG. 3 is a side view of the design of FIG. 1;

FIG. 4 is a front view of the design of FIG. 1;

FIG. 5 is a rear view of the design of FIG. 1;

FIG. 6 is a top view of the design of FIG. 1;

FIG. 7 is a bottom view of the design of FIG. 1; and,
FIG. 8 is a side view of the design of FIG. 1 installed on a kayak.

The broken lines represent portions of the kayak illumination device; the additional broken lines in FIG. 8 represent environment; all broken lines form no part of the claimed design.

1 Claim, 7 Drawing Sheets
